UNITED STATES PATENT OFFICE

114,575

DESIGN FOR A PIVOTAL DRIVE UNIT FOR CONVEYERS OR THE LIKE

Samuel I. Bousman, Denver, Colo., assignor to
Colorado Iron Works Company, Denver, Colo.,
a corporation of Maine

Application July 18, 1938, Serial No. 78,552

Term of patent 14 years

To all whom it may concern:

Be it known that I, Samuel I. Bousman, a citizen of the United States, residing at Denver, in the county of Denver and State of Colorado, have invented a new, original, and ornamental Design for a Pivotal Drive Unit for Conveyers or the like, of which the following is a specification, reference being had to the accompanying drawing, forming part thereof.

Figure 1 is a perspective view of a pivotal drive unit for conveyers or the like, showing the new design.

Figure 2 is an elevation looking in the direction of arrow 2 of Figure 1.

I claim:

The ornamental design for a pivotal drive unit for conveyers or the like, as shown.

SAMUEL I. BOUSMAN.
